LEVELING DEVICE FOR FURNITURE AND THE LIKE

Harold C. Sundell, Hollywood, Fla., assignor to
Frank J. Curran, Downers Grove, Ill.

Application July 23, 1957, Serial No. 673,718

7 Claims. (Cl. 45—139)

My invention relates to a leveling device for furniture and the like, and more specifically, to a device for attachment to the ends of furniture legs, props, or supports, such as, for instance, the legs of tables and chairs, to eliminate tilting or rocking when the furniture rests on or against an uneven floor or other supporting surface.

Conventional devices of this type employ a container or receptacle containing a quantity of a highly viscous substance, such as bouncing putty, which, when the device is interposed between the end of a table leg or the like and its supporting surface, is acted on by a piston that applies the weight of the furniture to the putty. The application of weight to the putty causes the putty to slowly deform and flow whereby a reduction in the effective length of the device, and thus of the furniture leg to which the device is attached, is achieved. When a piece of furniture having one of these devices secured to the end of each leg rests on an uneven floor, at least one of the legs, if the piece of furniture is a four-legged piece of furniture, will initially not contact the floor, with the familiar tilting and rocking action resulting. The weight of the furniture on the remaining legs causes a slow flow of the bouncing putty within the leveling devices that carry a disproportionate part of the weight, with a consequent shortening of their effective lengths, and thereby permit all of the legs to contact the floor, whereby the rocking and tilting action is eliminated.

However, conventional leveling devices of this type do not permit the floor contacting portions thereof to tilt for alignment with a floor surface that is canted with respect to a furniture leg, and consequently marring of the floor surface is a frequent occurrence where these devices are used. Moreover, they frequently are not adequately sealed against leakage and their shapes make them difficult to keep clean.

A principal object of my invention is to provide a leveling device which eliminates the conventional piston arrangement and permits the device to accommodate itself to canted surfaces.

A further object of the invention is to provide a leveling device that is readily attached to the legs of chairs, tables, cabinets, machinery, and the like without extensive modification of the leg structure.

Still a further object of the invention is to provide a leveling device that is readily adapted for a wide range of uses as a compensating device between the end of a prop or brace member that is used to support the load, and the surface against which the prop or braced member is to bear, thus eliminating the necessity for the exact alignment and squaring off of such members with respect to said supporting surfaces.

Yet another object of the invention is to provide a leveling device that is of streamlined shape and completely sealed against leakage.

Still another object of the invention is to provide a leveling device which is economical of manufacture, convenient in application, and highly efficient and long wearing in use.

2

Other objects, uses, and advantages will be obvious or become apparent from a consideration of the following detailed description and the application drawings.

In the drawings:

5 Figure 1 is a fragmental perspective view showing the lower portions of the legs of the table or the like illustrating a preferred embodiment of my invention applied thereto;

10 Figure 2 is a vertical cross section through the lower end of one of the table legs shown in Figure 1 as well as the leveling device that is attached thereto, illustrating the appearance of the various elements of the device when the leg is spaced somewhat from the floor;

15 Figure 3 is a view similar to that of Figure 2 illustrating the various elements of the device when the leg rests or bears on a canted floor surface;

20 Figure 4 is a fragmental elevational view of a modified form of the device shown applied to the end of a chair leg;

25 Figure 4a is a perspective view of an appropriate device for nailing the invention of Figure 4 to a furniture leg; and

Figure 5 is an elevational view of the device of Figure 2 shown applied between the end of a generally horizontally disposed prop and a canted generally vertical supporting surface.

30 Referring first to Figures 1 through 3, reference numeral 10 generally indicates a preferred embodiment of the invention applied to the ends of each furniture leg 12 which are assumed to support a table or chair but may be assumed to support any other similar form of structure, such as a cabinet, a machine, or any other device employing four legs as a support.

35 As seen in Figure 2, each device 10 comprises a pair of cup shaped members 14 that are positioned on either side of a diaphragm member 16. The cup-shaped members 14 may be formed from an appropriate resiliently flexible material such as rubber or rubber like substances, and each member 16 includes an annular circumambient rim portion 15 that projects laterally and outwardly of the respective members 14. The diaphragm member 16 is a relatively thin member that may be formed from any appropriate relatively rigid or hard substance, such as sheet metal or plastic, and includes a central perforation or vent 20. The diaphragm is proportioned to be received between rims 15 of members 14.

40 The members 14 and 16 thus form a pair of compartments or chambers 22 and 24 which are placed in communication by the perforation or vent 20 of the diaphragm member.

45 The lower member 14 is preferably formed with a relatively flat end portion 26 which may be annular in configuration and which carries in the illustrated embodiment a glider member 28. A conical or spiral helical compression spring 30 is interposed between the diaphragm member 16 and the portion 26 of the lower cup-shaped member 14.

50 Compartments 22 and 24 are filled or substantially filled with the substance known in the trade as bouncing putty. Bouncing putty is a solid elastic product of a reaction between a silicone oil and a compound of boron, such as, for example, boric acid, with the addition of a filler, such as lithopone. Bouncing putty deforms slowly under the slightest force, like a very viscous liquid, but it resists sudden forces as if it were a solid. It will not flow quickly, but when placed in a container, it will spread out merely under its own weight and eventually cover the bottom of the container.

55 60 65 70 The device 10 includes a generally cup shaped housing member 32 which includes a circumambient rim portion 34 that is formed during assembly of the device to

clamp the rims 15 of members 14 against diaphragm member 16.

When the device 10 is not under stress, the elements thereof appear substantially as shown in Figure 2, wherein the lower surface 36 of glider member 28 is shown spaced above the surface 38 of the floor upon which legs 12 are adapted to rest.

In the embodiment of Figures 1 through 3, the device 10 is applied to a table leg 12 by forming a recess 40 in the end of the leg and bonding the housing member 32 to the leg material dening this recess in any suitable manner, as by appropriate adhesives or the like.

When a table or chair including legs 12 having devices 10 applied thereto is first placed on an uneven floor that includes canted surface 38, the weight of the piece of furniture is supported principally upon two diagonally opposed legs. Since legs for tables, chairs, and the like are ordinarily all of the same length, when the surface 38 is irregular or a portion thereof is canted (as shown in Figure 2), ordinarily one of the legs 12 will be spaced above the floor somewhat as shown in Figure 2, which means that without the device 10 applied to each leg, the piece of furniture would tilt or rock back and forth on two diagonally opposed legs. The weight of the piece of furniture is thus disproportionately applied to these two diagonally opposed legs, which will initially cause the bouncing putty in chamber 24 of the devices 10 secured to these legs to flow upwardly through perforation 20 of diaphragm member 16 into chamber 22. This process continues until the weight of the piece of furniture is substantially equally distributed over the four legs 12, during which time the lower members 14 flex sufficiently to permit all of the glider members 28 to be flush with the surface of the floor. This tends to distort the flexible members 14 of the devices 10 somewhat as indicated in Figure 3, the upper member 14 bulging somewhat and the lower member 14 partially collapsing.

In this condition, the devices 10 will support the table or chair having legs 12 indefinitely, the devices 10 insuring that the familiar tilting or rocking action is eliminated.

When the table or chair is lifted from the supporting surface 38, spring 30 urges portion 26 of the lower member 14 away from diaphragm member 16 to restore the devices 10 to the position of Figure 2. The excess bouncing putty that has passed to chamber 22 is restored to chamber 24 by the resilience of the material forming upper member 14.

If the chair or table that includes legs 12 is again applied to a canted or uneven supporting surface, the leveling action again repeats itself to provide a steady support for the piece of furniture. Where the supporting surface is initially level, some putty flowage will occur, but it will be uniform for all the devices 10 carried by the particular piece of furniture.

In the embodiment of Figure 4, a device 10a is illustrated which is identical to the device 10 except that it has secured to the housing member 32 a nail or tack shank 50, which is driven to the end of the leg 12. A tool such as that indicated in Figure 4a may be employed to drive nail 50 into leg 12, annular member 51 being applied against rim 34 of the housing and a hammer being applied to the end 52 of handle 53.

In the embodiment of Figure 5, a device 10 is applied between a generally horizontally disposed brace 55 and a substantially vertical but slightly canted surface 56. The prop 55 may be braced between a piece of machinery or a refrigerator or the like that is positioned adjacent a wall 58 of a building. The housing 32 of the device 10 in Figure 5 may be affixed to the end 60 of prop or brace 55 by an appropriate adhesive.

Assuming that the piece of machinery or refrigerator or the like bears against the wall 58 through brace 55, the device 10 of Figure 5 will be distorted somewhat as

shown, but will adequately transmit and support the load desired.

One of the principal advantages of my invention is that the flexible members 14 permit the portion 26 and the glider 28 carried thereby to tilt with respect to the remainder of the device and rest evenly on a canted or inclined supporting floor surface.

The devices 10 and 10a thus provide a uniform and steady support for the piece of furniture, machinery, or the like, regardless of how uneven a floor or other supporting surface may be.

The streamlined shape of the illustrated embodiments makes the device easy to clean and dust. The invention will not gather strings or cords from floor mops or the like, and is completely sealed against putty leakage by the clamping action of housing rim 34 on rims 15 of the cup shaped members 14.

If it is found desirable to slide a table or the like across a floor, a good portion of the noise involved is absorbed by the devices 10 and 10a. If the piece of furniture is to be permanently mounted, the device 10 or 10a may be cemented or otherwise affixed to the floor surface. The glider member 28, the lower surface of which is usually substantially smooth and of the anti-friction type, may be eliminated, in which case the material from which the lower member 14 is formed will oppose sliding movement.

The material from which the glider member 28 is made is optional though metallic and plastic substances are contemplated. In damp climates the substance employed should be of the rust proof type.

The proportions and thickness of the material forming members 14 as well as the resilience of these members and of spring 30 and the size of vent 20 may be varied to provide the particular operating characteristics desired for a device 10. In some instances, a greater flexibility with a larger volume of putty flow may be desirable, while in others, a greater stiffness with a lesser volume of putty flow may be preferred.

The foregoing description and the drawings are given merely to explain and illustrate my invention, and the invention is not to be limited thereto, except in so far as the appended claims are so limited, since those skilled in the art who have my disclosure before them will be able to make modifications and variations therein without departing from the scope of the invention.

In the appended claims, the term "furniture and the like" is intended to mean tables, chairs, machinery, cabinets, work benches, and all other structures having legs, struts, props, or the like which bear against a surface to support or brace a load.

I claim:

1. A leveling device for furniture and the like comprising a flexible sealed container having a relatively flat end portion, a diaphragm member mounted in said container and separating said container into compartments, said diaphragm member extending generally parallel to said flat end portion and being formed with a perforation that places said compartments in communication with each other, resilient means acting on said container and biasing said flat end portion away from said diaphragm member, said compartments being substantially filled with bouncing putty.

2. A leveling device for furniture and the like comprising a flexible sealed container having a relatively flat end portion, a diaphragm member mounted in said container and separating said container into compartments, said diaphragm member extending generally parallel to said flat end portion and being formed with a central perforation that places said compartments in communication with each other, helical spring means interposed between said diaphragm member and said flat end portion and biasing said flat end portion away from said diaphragm member, said compartments being substantially filled with bouncing putty.

3. A leveling device adapted to be secured to the end of a furniture leg or the like comprising a flexible sealed container having a relatively flat end portion, a diaphragm member mounted in said container and separating said container into two compartments, said diaphragm member extending generally parallel to said flat end portion and being formed with a perforation that places said compartments in communication with each other, helical spring means interposed between said diaphragm member and said flat end portion and biasing said flat end portion away from said diaphragm member, said compartments being substantially filled with bouncing putty, a rigid housing in which said container is mounted, said flat end portion of said container extending outwardly of said housing, and means for securing said housing to the furniture leg.

4. A levelling device adapted to be secured to the end of a furniture leg or the like comprising a diaphragm member, a flexible cup shaped member positioned on either side of said diaphragm member, each of said cup shaped members including a rim portion that is placed in contact with said diaphragm member, whereby said diaphragm member and said cup shaped members form a pair of spaced compartments, said diaphragm member being perforated to place said compartments in communication with each other, one of said cup shaped members being formed with a relatively flat end portion, a dished housing member being received about the other of said cup shaped members and including means for clamping said cup shaped members against said diaphragm, helical compression spring means interposed between the flat end portion of said one cup shaped member and said diaphragm, each of said compartments being substantially filled with bouncing putty, and means for securing said housing member to the furniture leg.

5. A leveling device adapted to be secured to the end of a furniture leg or the like comprising a diaphragm member, a flexible cup shaped member positioned on either side of said diaphragm member, said cup shaped members each including a circumambient rim portion that projects laterally thereof, said rim portions being placed in contact with said diaphragm member, whereby said diaphragm member and said cup shaped members form a pair of spaced compartments, said diaphragm member being perforated to place said compartments in communication with each other, one of said cup shaped members being formed with a relatively flat end portion, a dished housing member being received about the other of said cup shaped members, said housing member including a circumambient rim portion clamped about said rim portions of said cup shaped members and said dia-

phragm, helical compression spring means interposed between said flat end portion of said one cup shaped member and said diaphragm, each of said compartments being substantially filled with bouncing putty, and means for securing said housing member to the furniture leg.

6. A leveling device adapted to be interposed between the ends of furniture legs or the like and the supporting surface against which the furniture bears comprising a flexible sealed container substantially filled with bouncing putty, said container being formed with a relatively flat end portion and comprising a pair of compartments in restricted communication with each other, said bouncing putty being received in said compartments, said device being attached to the end of a furniture leg or the like to place said flat end portion in contact with the supporting surface against which the furniture bears, whereby, the bouncing putty flows between said compartments under the action of the force transmitted to the supporting surface through the device, and if said surface is canted with respect to the furniture leg, said container flexes to permit said flat end portion to rest flush against the canted supporting surface.

7. A leveling device for furniture and the like comprising a resiliently flexible sealed container substantially filled with bouncing putty, said container comprising a pair of juxtaposed compartments in restricted communication with each other, one of said compartments being at an end portion of the container, said bouncing putty being received in said compartments, resilient means acting on said container to bias said end portion outwardly of the device, means for securing the device to the furniture or the like with said end portion thereof projecting away from the furniture or the like, and rigid means for shielding the other container from external compressive forces, said rigid means being proportioned to permit expansion of said other container, whereby, when said end portion of the device is pressed against a supporting surface, the bouncing putty flows between said compartments to effect contraction of said one compartment and expansion of said other compartment, said resilient means on release of pressure on the device effecting restoration of said one compartment to its initial size, the compressive action of said container on the bouncing putty in said other compartment causing a reverse flow of the bouncing putty between said compartments.
